UNITED STATES PATENT OFFICE.

ARTHUR T. TIMEWELL, OF CHICAGO, ILLINOIS, ASSIGNOR TO ALBERT DICKINSON, OF SAME PLACE.

MACHINE FOR TRANSFERRING AND SEWING FILLED SACKS.

SPECIFICATION forming part of Letters Patent No. 607,809, dated July 19, 1898.

Application filed July 6, 1897. Serial No. 643,510. (No model.)

To all whom it may concern:

Be it known that I, ARTHUR T. TIMEWELL, a citizen of the United States, residing in Chicago, in the county of Cook and State of Illinois, have invented a new and useful Improvement 5 in Machines for Transferring and Sewing Filled Sacks, of which the following is a specification.

My invention relates to machines for sewing filled sacks and transferring or carrying the filled sacks from the filling, packing, or weighing apparatus to and through the sewing mechanism. In machines heretofore in use for this purpose—such, for example, as those 10 heretofore patented to me in Letters Patent Nos. 476,778, 539,455, 548,029, and 562,438—it has been customary to insert the empty sack in an opening and closing traveling holder, which serves to hold the sack open while being filled and then to hold its mouth closed 15 or in position for sewing while the sack is being conveyed past the sewing mechanism and sewed. In filling sacks, however, with finely pulverized or powdered material—for example, such as flour—it is customary and necessary or desirable to employ a rotary or screw packer working in a cylindrical filling-tube of substantially the diameter of the sack, which enters the sack and holds the mouth of it 20 open while it is being filled and the flour or other material packed therein by operation of the rotary packer. Such a cylindrical tube or device for holding the sack open while being filled is of course not adapted to collapse 25 or to hold the mouth of the sack closed while it is being sewed or conveyed past the sewing mechanism.

The object of my invention is to provide a filled-sack sewing and transferring machine 30 adapted to do this work above mentioned or to transfer or convey the filled sack from the scale or other platform of the rotary-packer filling mechanism to the traveling holder, which latter is adapted to receive the sack 35 after it is filled and to hold its mouth closed and to convey it past the sewing mechanism while its mouth is so held closed or in position for sewing.

To this end my invention consists, prima-

rily, in the combination, with a filled-sack 50 conveyer, of a sewing mechanism and a traveling sack-holder adapted to receive the filled sack from the conveyer and hold the mouth of the sack closed while being conveyed past the sewing mechanism and sewed. The traveling 55 holder consists, preferably, of two straight opening and closing clamp-bars, between which when open or separated the filled sack is conveyed and suspended by the conveyer and which then close or clamp together in a 60 straight line and hold the sack securely while the holder moves forward and conveys the sack past the sewing mechanism.

My invention also consists in the novel construction of parts and devices and in the novel 65 combinations of parts and devices herein shown and described, and specified in the claims.

In the accompanying drawings, forming a part of this specification, Figure 1 is a partial 70 side elevation showing the filled-sack conveyer and a portion of the mechanism for closing the traveling sack-holder. Fig. 2 is a partial plan view showing the traveling holder and sewing mechanism. Fig. 3 is a side elevation of the parts shown in Fig. 2. Fig. 4 is an enlarged partial horizontal section showing the means for moving or propelling the traveling holder. Fig. 5 is a section on line 55 of Fig. 2. Fig. 6 is a horizontal section on line 66 of 80 Fig. 3, showing the overhanging track for the movable side or bar of the traveling holder. Figs. 7, 8, and 9 are cross-sections on lines 77, 88, and 99, respectively, of Fig. 6. Fig. 10 is a bottom view of said overhanging track. Figs. 85 11 and 12 are sections on line 1111 and 1212, respectively, of Fig. 2. Fig. 13 is a plan view of the traveling holder. Fig. 14 is a section on line 1414 of Fig. 13, showing the holder, however, closed. Fig. 15 is a detail perspective view showing the end of one of the slides engaged by the traveling holder. Fig. 16 is a detail perspective view of the sewing mechanism and parts adjacent thereto; and Fig. 17 is a perspective view showing the sewing 90 mechanism portion of the machine, including the reciprocating sack-holder and the table upon which it reciprocates back and forth. 95

Fig. 18 is a view similar to Fig. 4, showing the holder during its return movement. Fig. 19 is a section on the line 19 19 of Fig. 2.

In the drawings like letters indicate like parts in all the figures.

In the drawings, A represents the frame of the machine or apparatus.

B is a conveyer or device for transferring the filled sack X from the scale C or other part of the sack-filling mechanism to and between the clamp bars or jaws of the traveling sack-holder D, by which the mouth of the sack is held closed and conveyed past the sewing mechanism F.

15 The filled-sack conveyer B may be of any suitable construction adapted to grasp the sack at opposite points of its mouth and cause the edges $x x$ of the sack-mouth to somewhat approach each other and thus enter between the clamp bars or jaws D' D² of the traveling sack-holder. A simple and convenient construction of filled-sack conveyer is illustrated in the drawings as being the form I prefer to employ, and consists of a pair of reverse-acting lazy-tongs b b, pivoted together at their bend or angle b' and connected at their upper ends by pivoted links b² b² to a pulley b³, which travels on an inclined endless track B'. By simply inserting the ends or prongs of the 25 tongs within the mouth of the filled sack the weight of the filled sack itself causes the prongs or gripping-jaws b⁴ b⁴ of the conveyer to properly grip the edges of the sack-mouth at opposite points and thus to cause the edges 30 of the sack to extend in parallel lines and near enough together to enter properly between the open ends of the clamp-bars D' D² of the traveling holder.

By employing an inclined endless track B' 40 for the conveyer B to run upon it may be caused to move back and forth by its own gravity, except at the ends or turns of the track, where it inclines upward and where revolving pushers or wheels B² B² may be employed to push or convey it up the inclines. To tighten the prongs or gripping-jaws b⁴ b⁴ of the conveyer in or against the sack and lift the sack off the platform C', I provide the track B' with a movable or hinged section B³, the free end of which is adapted to be raised by a treadle B⁴ through the connecting-link B⁵, lever B⁶, and link B⁷. As soon as the sack is lifted sufficiently to clear the platform C' of the scales the conveyer will at once begin 50 to move down the incline and carry the sack between the jaws or clamping-bars D' D² of the traveling sack-holder D. The conveyer-track B' is provided with a depression B⁸, so that after the clamping-bars D' D² close upon 55 the sack, so as to properly hold it and support its weight, the conveyer B may on entering this depressed portion B⁸ of the track be relieved of the weight of the sack and be automatically released therefrom and with- 60 drawn out of the way as the farther or subsequent paths of the sack and of the conveyer diverge or separate from each other.

The transversely-movable or opening and closing jaw or clamping-bar D² of the traveling holder is connected to its fellow D' by a pin d, secured to one of said bars near the front end thereof and entering a hole in the other bar. The meeting faces of the clamp-bars are provided one with a groove d' and the other with a tongue or rib d² to increase 75 the grip of the bars upon the edges of the sack, and for the same reason I make one of said meeting faces, preferably the tongue, of rubber.

The holder is moved or propelled forward 80 along a track or guideway G, having a slot g for the mouth edges of the sack to project through and side rails or ledges g', preferably, by means of a rack d⁸, formed on the bar D', the connecting-pin d causing the bar 85 D² to move with the bar D', which engages a pinion d⁴ on the shaft d⁵. A weight d⁶, connected by a line d⁷, passing over pulleys d⁸ d⁹, serves to return the holder to position. The transversely-movable bar or jaw D² is operated or opened and closed against its fellow 90 to clamp the sack between them by means of a reciprocating slide D³, which is connected to a rack D⁴, that engages a gear D⁵ on the rock-shaft D⁶, said rock-shaft having an arm D⁷, connected by a link D⁸ with a treadle or foot-lever D⁹.

The side rail g' opposite the holder-closing slide D³ is provided with antifriction-rollers g², and the holder-closing slide D³ is provided with similar antifriction-rollers g² for the holder to slide against as it moves longitudinally forward along the track G. The track G is also furnished with an overhanging guide G', having a depending ledge g⁴, against 105 which the antifriction-rollers d¹⁰ on the transversely-movable bar D² of the holder bear as the holder travels forward and back. Two of these rollers d¹⁰ are located near the front end of the bar D² and one near the rear end 110 thereof, as is clearly indicated in Fig. 6. The rollers d¹⁰ bear against one side of the ledge g⁴ as the bar D² travels forward and serve to keep the holder closed, and they bear upon the opposite side of the ledge g⁴ as the bar D² 115 moves backward, and thus hold the holder open. In order to permit the rollers d¹⁰ to first pass on one side of the ledge and to return upon the other side, the ledge or guide-rail g⁴ is made sectional, with gaps between 120 its sections, and its two end sections g⁵ g⁵ are preferably made hinged or movable by pivot-pins g⁶ and furnished with inclined ends g⁷ and springs g⁸, as shown in Fig. 18, so that when the holder D has advanced sufficiently 125 far to carry the sack entirely past the sewing mechanism F as the rollers d¹⁰ reach the ends of the sections g⁵ g⁵ said sections will be swung by the springs g⁸ against the ledge g³, which limits their movement, as shown in 130 Fig. 4, and as the bar D² begins its backward movement the rollers d¹⁰ will engage the sections g⁵ g⁵ and be guided by them to the opposite side of the guide-ledge g⁴ (see dotted

line, Fig. 6) and will thus force the transversely-movable bar D² of the holder to separate from its fellow member D', and thus permit the sewed sack to drop out or be discharged. At this time, the rear end of the rack d³ having passed the gear d⁴, the weight d⁶ begins to return the holder to its original position ready to receive another sack, and the springs g⁸, having thrown the pivoted sections g⁵ g⁵ into the positions indicated by the dotted lines in Fig. 6, may thus cause the rollers d¹⁰ on the holder to pass back on the opposite side of the guide-rail g⁴ g⁵ g⁵, and thus cause the bar D² to remain open or separate from the bar D' on the return movement of the holder. This makes a convenient means for automatically returning the holder open; but other suitable means or mechanism for this purpose may be employed, if desired.

The sewing mechanism F may be of any suitable construction known to those skilled in the art and needs no detailed description. The sewing mechanism which I prefer to employ and which I have illustrated in the drawings is similar to that shown and described in my former patents above referred to or to that shown and described in my application, Serial No. 578,620, filed February 30, 1896, and patented January 11, 1898, No. 597,075. It comprises a frame or arm F', attached to the bed-plate A of the frame at one side of the slotted guideway or track G and overhanging said track, and a needle f and looper and presser-foot f' and thread holder and cutter, as will be readily understood by those skilled in the art by reference to my said former patents. The sewing mechanism is operated from the driven shaft F² through a friction-clutch connecting mechanism F³ F⁴, which is operated automatically by the traveling holder D engaging a slide F⁵, projecting in the path of said holder. A similar slide F⁶ operates the thread holder and cutter. The slides F⁵ and F⁶ are each provided with a hinged section F⁷, held in position by a spring F⁸, so that when the holder moves forward said slides will be operated as required, while by the turning of said hinged sections 50 on their pivots the holder-bar D' may return along the same path without reciprocating said slides.

To assist in propelling the holder D forward, I provide in addition to the pinion d⁴ on the shaft d⁵ a second pinion d¹¹ on a shaft d¹², which also engages the rack d³. The shafts d⁵ and d¹² are geared together by bevel-gears d¹³ d¹⁴ d¹⁵ d¹⁶, the gears d¹⁴ and d¹⁵ being on a connecting-shaft d¹⁷. Motion is communicated to the shaft d⁵ from the driving-shaft H through a clutch H', which is thrown out of engagement with its fellow H² when the holder-bar D' is making its return movement under the impulse of the weight d⁶, so that the rack d³ may thus turn the pinions d⁴ d¹¹ in the opposite direction. The clutch H' is thus automatically thrown out of engagement with

its fellow by a spring H³, acting against the clutch-lever H⁴. The clutch-lever H⁴ is moved in the opposite direction to hold the clutch H' in gear by the same treadle D⁹ and rock-shaft D⁶ which are employed to operate the slide D³, that actuates the transversely-movable bar D² of the traveling holder D. This is done by providing said rock-shaft D⁶ with an arm D¹⁰, connected by a link H⁵ with an arm H⁶ on a rock-shaft H⁷, which has a second arm H⁸ connected by a link H⁹ with the clutch-lever H⁴. The clutch H' is held in engagement with its fellow by the operator holding the treadle D⁹ depressed until the front end of the holder D engages the slide K and pushes it back, when the pin k on said slide K engages the arm H⁶, and thus holds the clutch H' in engagement, so that the operator may then take his foot off the treadle. The link H⁵ has a slot h to connect it with the arm H⁶ to permit the link to be operated by the treadle D⁹ and rock-shaft D⁶ before the traveling holder strikes the slide K. The slide K projects, like the slides F⁵ F⁶, in the path of the traveling holder, and, like them, it is provided with a hinged section K', held in position by a spring K², to permit the holder to make its return movement without operating the slide.

I claim—

1. In a filled-sack transferring and sewing mechanism, the combination with a conveyer for the filled sack and a sewing mechanism of a traveling sack-holder comprising a pair of opening and closing clamps, between which, when open, the mouth of the filled sack may be slipped or moved; the two opening and closing clamps of said sack-holder being separate and unconnected when open to enable the mouth of the filled sack to enter between said clamps, and to be slipped or moved forward lengthwise of the clamps into position between them, substantially as specified.

2. The combination with a filled-sack conveyer of a traveling sack-holder comprising a pair of clamp-bars, between which, when open, the mouth of the filled sack may be slipped or moved by said conveyer, and a sewing mechanism, substantially as specified.

3. The combination with a filled-sack conveyer of a traveling sack-holder comprising a pair of clamp-bars, between which, when open, the mouth of the filled sack may be slipped or moved by said conveyer, a sewing mechanism, and a slotted track for said holder, substantially as specified.

4. The combination with a filled-sack conveyer of a traveling sack-holder comprising a pair of clamp-bars, between which, when open, the mouth of the filled sack may be slipped or moved by said conveyer, a sewing mechanism, a slotted track for said holder, and means for operating the transversely-movable bar of said holder, substantially as specified.

5. The combination with a filled-sack conveyer of a traveling sack-holder comprising

- a pair of clamp-bars, between which, when open, the mouth of the filled sack may be slipped or moved by said conveyer, a sewing mechanism, a slotted track for said holder, 5 means for operating the transversely-movable bar of said holder, and means for moving said holder along said track, substantially as specified.
6. The combination with a filled-sack conveyer, of a traveling sack-holder comprising a pair of opening and closing clamp-bars between which when open the mouth of the filled sack is slipped or moved by said conveyer, substantially as specified.
- 15 7. The combination with a filled-sack conveyer, of a traveling sack-holder comprising a pair of opening and closing clamp-bars between which when open the mouth of the filled sack is slipped or moved by said conveyer, 20 the meeting faces of said clamp-bars having the one a groove and the other a tongue or rib to increase the grip of said clamp-bars upon the mouth of the sack when the clamp-bars are closed, substantially as specified.
- 25 8. The combination with a filled-sack conveyer, of a traveling sack-holder comprising a pair of opening and closing clamp-bars between which when open the mouth of the filled sack is slipped or moved by said conveyer, 30 the meeting faces of said clamp-bars having the one a groove and the other a tongue or rib to increase the grip of said clamp-bars upon the mouth of the sack when the clamp-bars are closed, and one of said meeting faces of 35 said clamp-bars being of rubber, or like material, substantially as specified.
9. In a filled-sack-sewing machine, the combination with a sewing mechanism of a traveling sack-holder comprising a pair of opening and closing clamps, between which, when open, the mouth of the filled sack may be slipped or moved, and then clamped by the closing of the clamps, said clamps when open being separate and disconnected at their sack-receiving end to enable the mouth of the sack to be entered between them and slipped or moved lengthwise of the clamps into position between them, substantially as specified.
10. In a filled-sack-sewing machine, the 50 combination with a sewing mechanism, of a traveling sack-holder reciprocating forward and back in the same path, of a slide projecting in the path of the traveling holder for setting the sewing mechanism in operation, 55 said slide being provided with a hinged section to permit the holder to make its return movement in the same path without operating said slide, substantially as specified.
11. In a filled-sack-sewing machine, the 60 combination with a sewing mechanism, of a traveling sack-holder reciprocating forward and back in the same path, of a slide projecting in the path of the traveling holder for setting the sewing mechanism in operation, 65 said slide being provided with a hinged section to permit the holder to make its return movement in the same path without operat-
- ing said slide, and a second slide for operating the thread holder and cutter of the sewing mechanism and provided with a similar 70 hinged section, substantially as specified.
12. In a filled-sack-sewing machine, the combination with a sewing mechanism, of a traveling sack-holder, a track for the holder, and an overhanging guide for the holder 75 provided with a guide-rail for holding the transversely-movable clamp-bar of the holder closed, said guide-rail being sectional to permit said clamp-bar of the holder to open after the holder passes the sewing mechanism, substantially as specified.
13. In a filled-sack-sewing machine, the combination with a sewing mechanism, of a traveling sack-holder, a track for the holder, and an overhanging guide for the holder provided with a guide-rail for holding the transversely-movable clamp-bar of the holder closed, 80 said guide-rail being sectional to permit said clamp-bar of the holder to open after the holder passes the sewing mechanism, and said guide-rail being provided with a hinged section to cause the transversely-movable clamp-bar of the holder on its return movement to open or separate from its fellow, substantially as specified.
14. In a filled-sack-sewing machine, the combination with an opening and closing sack-holder adapted to receive when open a filled sack, and a filled-sack conveyer provided with devices for grasping and suspending a filled sack from and by opposite points of its mouth so as to draw its mouth edges together and adapt them to enter between the clamp-bars of the holder, substantially as specified.
15. In a filled-sack-sewing machine, the combination with an opening and closing sack-holder adapted to receive when open a filled sack, and a filled-sack conveyer provided with devices for grasping and suspending a filled sack from and by opposite points of its mouth so as to draw its mouth edges together and adapt them to enter between the clamp-bars of the holder, and a sewing mechanism, substantially as specified.
16. The combination with a traveling sack-holder, of a track for the holder, a rack on the holder, driving-pinion engaging said rack to propel the holder forward, a driving-shaft, a clutch between said driving shaft and pinion, and a slide connected with said clutch and projecting in the path of said holder and engaged thereby to hold the movable member of the clutch in engagement with its fellow, and a spring for opening the clutch when the holder passes said slide, substantially as specified.
17. The combination with a traveling sack-holder, of a track for the holder, a rack on the holder, driving-pinion engaging said rack to propel the holder forward, a driving-shaft, 120 a clutch between said driving shaft and pinion, and a slide connected with said clutch and projecting in the path of said holder and engaged thereby to hold the movable member of the clutch in engagement with its fellow, and a spring for opening the clutch when the holder passes said slide, substantially as specified.
18. The combination with a traveling sack-holder, of a track for the holder, a rack on the holder, driving-pinion engaging said rack to propel the holder forward, a driving-shaft, 125 a clutch between said driving shaft and pinion, and a slide connected with said clutch and projecting in the path of said holder and engaged thereby to hold the movable member of the clutch in engagement with its fellow, and a spring for opening the clutch when the holder passes said slide, substantially as specified.

engaged thereby to hold the movable member of the clutch in engagement with its fellow, and a spring for opening the clutch when the holder passes said slide, said slide having a hinged section to prevent said slide being operated on the return movement of said holder, substantially as specified.

18. The combination with a traveling sack-holder, of a track for the holder, a rack on the holder, driving-pinion engaging said rack to propel the holder forward, a driving-shaft, a clutch between said driving shaft and pinion, and a slide connected with said clutch and projecting in the path of said holder and engaged thereby to hold the movable member of the clutch in engagement with its fellow, a spring for opening the clutch when the holder passes said slide, said slide having a hinged section to prevent said slide being operated on the return movement of said holder, and a weight and line for returning the holder, substantially as specified.

19. The combination with a traveling sack-holder, of a track for the holder, a rack on the holder, driving-pinion engaging said rack to propel the holder forward, a driving-shaft, a clutch between said driving shaft and pinion, and a slide connected with said clutch and projecting in the path of said holder and engaged thereby to hold the movable member of the clutch in engagement with its fellow, a spring for opening the clutch when the holder passes said slide, said slide having a hinged section to prevent said slide being operated on the return movement of said holder, and a weight and line for returning the holder, an overhanging guide for the holder provided with a sectional guide-rail having hinged sections for holding the transversely-movable bar of the holder open on the return movement of the holder, substantially as specified.

20. In a filled-sack-sewing machine, the combination with a sewing mechanism, of a traveling sack-holder, a track for the holder, and an overhanging guide for the holder provided with a guide-rail for holding the transversely-movable clamp-bar of the holder closed, said guide-rail being sectional to permit said clamp-bar of the holder to open after the holder passes the sewing mechanism, and said holder being provided with rollers to bear against said guide-rail, substantially as specified.

21. In a filled-sack-sewing machine, the combination with a sewing mechanism, of a traveling sack-holder, a track for the holder, and an overhanging guide for the holder provided with a guide-rail for holding the transversely-movable clamp-bar of the holder closed, said guide-rail being sectional to permit said clamp-bar of the holder to open after the holder passes the sewing mechanism, and said guide-rail being provided with hinged sections to cause the transversely-movable clamp-bar of the holder on its return movement to open or separate from its fellow, said holder being provided with rollers to bear

against said guide-rail, substantially as specified.

22. In a filled-sack-sewing machine, the combination with an opening and closing sack-holder adapted to receive when open a filled sack, and a filled-sack conveyer provided with devices for grasping and suspending a filled sack from and by opposite points of its mouth so as to draw its mouth edges together and adapt them to enter between the clamp-bars of the holder, said filled-sack conveyer consisting in a pair of reversely-acting lazy-tongs, substantially as specified.

23. In a filled-sack-sewing machine, the combination with an opening and closing sack-holder adapted to receive when open a filled sack, and a filled-sack conveyer provided with devices for grasping and suspending a filled sack from and by opposite points of its mouth so as to draw its mouth edges together and adapt them to enter between the clamp-bars of the holder, a sewing mechanism, said filled-sack conveyer consisting in a pair of reversely-acting lazy-tongs, and a track for said filled-sack conveyer to travel upon, substantially as specified.

24. In a filled-sack-sewing machine, the combination with an opening and closing sack-holder adapted to receive when open a filled sack, and a filled-sack conveyer provided with devices for grasping and suspending a filled sack from and by opposite points of its mouth so as to draw its mouth edges together and adapt them to enter between the clamp-bars of the holder, a sewing mechanism, and a track for said filled-sack conveyer, having a hinged or movable section for lifting the filled sack from the platform or support upon which it rests, substantially as specified.

25. In a filled-sack-sewing machine, the combination with an opening and closing sack-holder adapted to receive when open a filled sack, and a filled-sack conveyer provided with devices for grasping and suspending a filled sack from and by opposite points of its mouth so as to draw its mouth edges together and adapt them to enter between the clamp-bars of the holder, a sewing mechanism, and a track for said filled-sack conveyer, having a hinged or movable section for lifting the filled sack from the platform or support upon which it rests, and mechanism for operating said hinged section, substantially as specified.

26. In a filled-sack-sewing machine, the combination with an opening and closing sack-holder adapted to receive when open a filled sack, and a filled-sack conveyer provided with devices for grasping and suspending a filled sack from and by opposite points of its mouth so as to draw its mouth edges together and adapt them to enter between the clamp-bars of the holder, a sewing mechanism, and an endless track for said filled-sack conveyer having downwardly and upwardly inclined portions, and wheels or pushers for

propelling said conveyer at the upwardly-inclined portions of said track, substantially as specified.

27. In a filled-sack-sewing machine, the combination with a sewing mechanism, of a traveling sack-holder reciprocating forward and back in the same path, of a slide projecting in the path of the traveling holder for setting the sewing mechanism in operation, said slide being provided with a hinged section to permit the holder to make its return movement in the same path without operating said slide, a rack and pinion for propelling the holder forward and a weight and connecting-line for returning the holder, substantially as specified.

28. In a filled-sack-sewing machine, the combination with a sewing mechanism, of a traveling sack-holder reciprocating forward and back in the same path, of a slide projecting in the path of the traveling holder for setting the sewing mechanism in operation, said slide being provided with a hinged section to permit the holder to make its return movement in the same path without operating said slide, a rack and pinion for propelling the holder forward and a weight and connecting-line for returning the holder, a slotted track for the holder, and an overhanging guide for the holder having a sectional guide-rail, substantially as specified.

29. In a filled-sack-sewing machine, the combination with a sewing mechanism, of a traveling sack-holder reciprocating forward

and back in the same path, of a slide projecting in the path of the traveling holder for setting the sewing mechanism in operation, said slide being provided with a hinged section to permit the holder to make its return movement in the same path without operating said slide, a rack and pinion for propelling the holder forward and a weight and connecting-line for returning the holder, a slotted track for the holder, and an overhanging guide for the holder having a sectional guide-rail, said holder having rollers engaging said sectional guide-rail, substantially as specified.

30. In a filled-sack-sewing machine, the combination with a sewing mechanism, of a traveling sack-holder reciprocating forward and back in the same path, of a slide projecting in the path of the traveling holder for setting the sewing mechanism in operation, said slide being provided with a hinged section to permit the holder to make its return movement in the same path without operating said slide, a rack and pinion for propelling the holder forward and a weight and connecting-line for returning the holder, a slotted track for the holder, and an overhanging guide for the holder having a sectional guide-rail, said holder having rollers engaging said sectional guide-rail, said sectional guide-rail having hinged sections, substantially as specified.

ARTHUR T. TIMEWELL.
